UNITED STATES PATENT OFFICE

171,002

CHAIR

Charles P. Molla, New Hyde Park, N. Y.

Application June 12, 1952, Serial No. 20,151

Term of patent 14 years

(Cl. D15—8)

To all whom it may concern:

Be it known that I, Charles P. Molla, a citizen of the United States, now residing at New Hyde Park, in the county of Nassau and State of New York, have invented a new, original, and ornamental Design for a Chair, of which the following is a specification, reference being had to the accompanying drawing, forming part thereof.

The figure is a perspective view of a chair, showing my new design.

I claim:

The ornamental design for a chair, as shown.

CHARLES P. MOLLA.
